[57] CLAIM

The ornamental design for an electric golf bag carrier,
as shown.

DESCRIPTION

FIG. 1 is a side elevational view of an electric golf bag carrier showing my new design;

FIG. 2 is a side elevational view of the side opposite
that shown in FIG. 1;

FIG. 3 is a front elevational view thereof;

FIG. 4 is a rear elevational view thereof, and

FIG. 5 is a top plan view thereof, the bottom being plain
and unornamented.

FIG. 3

FIG. 4
